ROTARY THUMBWHEEL VOLTAGE
DIVIDER SWITCH

Henry Gabrielian, Santa Ana, Calif., assignor to Electronic Engineering Co. of California, Santa Ana, Calif., a corporation of California

Filed Mar. 4, 1964, Ser. No. 349,319
10 Claims. (Cl. 338—200)

My invention relates to switched adjustable voltage dividers and more particularly to a novel type of voltage divider assembled upon the structure of a thumbwheel rotary switch.

Certain voltage divider circuits having desirable properties, such as the Wolff-Poggendorf voltage divider, have heretofore been adjusted in voltage output by employing a plurality of relays. With the Wolff-Poggendorf voltage divider each such relay was provided with contacts and connected so as to short one resistor of the voltage divider at the same time as a correspondingly valued resistor was unshorted in the opposite part of the device. This provides a constant-current mode of operation.

A significant simplification is achieved by the subject invention wherein a switch structure itself provides the necessary Wolff-Poggendorf switching mode and relays are not required.

Additionally, by mounting the resistors involved upon the mechanical switch structure, highly desirable short connecting leads are employed and freedom from cross-talk and interference is secured.

The saving in space, weight and cost over the relay embodiment of the prior art is obvious. These advantages become particularly important when multiple units of the voltage divider are considered, such as a three gang unit providing 0.1 volt steps from 0 to 99.9 volts.

A preferred embodiment of my invention employs a thumbwheel type switch having a plurality of stationary contacts arranged in concentric tracks, each with one rotary wiper contact. An additional, preferably outer track is also provided, having two circumferentially spaced wipers. The additional track is arranged to provide contact between a stationary contact and one wiper at any given time and with the other wiper at another given time, in which way I obtain the function of two tracks in a single track. Two groups of series-connected resistors are preferably mounted on the same card or board which carries the stationary contacts and are connected to these contacts such that when one resistor in one group is shorted by the rotation of the thumbwheel to a given position resistor of corresponding resistance value is unshorted in the other group. This provides a constant current circuit. The output is taken across one group of resistors. The resistance ratio is altered thereacross for each position of the thumbwheel and when an energizing source of voltage is provided the voltage at the output is altered in an equivalent manner, thus providing the adjustable voltage divider.

An object of my invention is to provide a switched constant current voltage divider.

Another object is to provide a switched voltage divider having fewer switching tracks than is ordinarily required.

Another object is to provide a compact switched voltage divider.

Another object is to provide a Wolff-Poggendorf voltage divider devoid of relays.

Other objects will become apparent upon reading the following detailed specification and upon examining the accompanying drawings, in which are set forth by way of illustration and example certain embodiments of my invention.

FIG. 1 shows a simplified schematic circuit of a single section Wolff-Poggendorf voltage divider,

2

FIG. 2 shows a three-section embodiment of the same, FIG. 3 shows the contact side of a switch board with the locations of the resistors indicated, and

FIG. 4 shows a rotor with wipers and the accompanying thumbwheel.

In FIG. 1 the first group of resistors is identified by numerals 1, 2, 4, 2'; these numerals also suggesting the relative resistance values required. That is, for a low impedance voltage divider the value of resistor 1 may be 10 ohms, of 2 20 ohms, of 4 40 ohms, and of 2' 20 ohms. For a high impedance divider these may be 10,000 ohms, 20,000 ohms, 40,000 ohms, and 20,000 ohms, respectively. Resistor 1" is connected in shunt between the first and second groups of resistors and has the resistance value corresponding to 1; i.e. 10 ohms or 10,000 ohms in the examples given.

The second group of resistors is identified by numerals 1, 2, 4, 2'. These have corresponding resistance values and are located "opposite" in the circuit having the same designation in the first group. That is, when resistor 1 is shorted out of circuit, resistor 1' is unshorted and placed in circuit; the same with resistors 2 and 2', and so on.

The input to the voltage divider is provided at E_i, as by a battery 10 or an equivalent regulated power supply. The output is taken from across all of the second group of resistors; i.e., at E_o.

The manner in which the voltage divider is adjusted is indicated generally by the arrow contacts and the adjacent shorting bars in FIG. 2. The adjustment will first be recited with respect to FIG. 1. When the thumbwheel switch is positioned at the "0" (zero) index thereof, resistors 1, 2, 4, 2' and 1" are in circuit and resistors 1, 2, 4, 2' are shorted. This, of course, makes the voltage E_o=0. With the thumbwheel in position "1", resistors 2', 4, 2, 1" and 1 are in circuit and resistors 2, 4, 2' and 1 are shorted. This inserts a resistor having a resistance value of 1 in the E_o shunt path and removes one of the same value from the first group of resistors. This gives a voltage output corresponding to unity and also keeps the current flowing in the complete series circuit constant, as is indicated by the "constant 1" legend in FIG. 1.

With the thumbwheel switch in position "2," resistors 1, 2, 4, 1" are in circuit and resistors 1, 4, 2 are shorted. This inserts resistor 2, having a resistance value of 2 in the E_o shunt path and removes one of the same value from the first group of resistors. This gives a voltage output corresponding to two and again keeps the current flowing in the complete series circuit constant. By unshorting one or more resistors at any one time in the group of resistors 1, 2, 4, 2' it is seen that a total resistance up to the value 9 in that arm may be placed in circuit. Thus, voltage values from zero to nine are caused to appear in the output circuit E_o, and the output voltage is adjustable over this range in unit increments.

Frequently it is desired that the adjustment of the voltage divider be over a greater range or with finer steps, or both, and this is obtained by duplicating the structure of FIG. 1 plural times with resistor values ten times greater in each decade from the smallest increment of adjustment to the largest.

Such a structure is shown in FIG. 2. The source of voltage 10 is as before, although this may have a larger value, as 100 volts. Variable resistor 11 is placed in series with source 10 to provide a fine adjustment of the voltage of that source to, say, exactly 100 volts. Across terminals 12 and 13, then, appears the input voltage E_i.

At the first decade to the left of terminal 12, the tens decade, resistors 1_t, 2_t, 4_t, 2'_t in the first group are connected in series; and to the left of terminal 13 resistors 1_t, 2_t, 4_t, 2'_t in the second group are connected in series.

These have the same relative resistance values as was set forth in considering FIG. 1; in this case 10,000 ohms for 1_t , 20,000 ohms for 2_t , etc.

Each of the eight resistors involved in this decade are connected to individual stationary contacts upon the card of the thumbwheel switch structure, as is shown in FIG. 3. In FIG. 2 these are contacts 14 and 15 as related to resistor 1_t . A shorting wiper 16 is disposed upon the rotor thumbwheel of the switch and is in an operative relation to contacts 14 and 15. A corresponding pair of contacts 17 and 18 connect to resistor 1_t and a shorting wiper (a movable contact) 19 is in an operative relation to these contacts. As will be later disclosed, the operation of the thumbwheel switch is such that when contacts 14 and 15 are not shorted by wiper 16 contacts 17 and 18 are shorted by wiper 19, and vice versa. Element 20 is schematic for an insulating actuating member that moves both wipers 16 and 19 together and dotted line 21 is schematic for the thumbwheel rotor, indicating that all wipers move together.

In the tens decade in FIG. 2 it will be noted that resistor 4_t is not shorted, for purposes of illustration. This contributes to the output voltage the voltage drop across 40,000 ohms, which is equivalent to 40 volts in the voltage divider of FIG. 2.

Through interconnecting terminals 22 and 23 a second decade, the units decade, is connected to the whole electrical structure of the ganged voltage divider of FIG. 2. The connection of the resistors, their relative resistance values, arrangement for shorting and unshorting, and so on are the same as for the tens decade just described. The resistors are given the subscript "u" to designate that they are a part of the *units* decade. These resistors have absolute values $\frac{1}{10}$ that of the tens decade.

In the units decade wiper 25 shorts resistor 2_u in the illustrative condition shown. Resistors 1_u , 2_u , 4_u are not shorted. The values of these resistors are 1,000, 2,000, 4,000 ohms, respectively. The contribution of this series is thus 7,000 ohms. This is equivalent to 7 volts in the voltage divider of FIG. 2. In this units decade, resistors 1_u , 2_u , 4_u are shorted by wipers 26, 27, 28, respectively, in order that the constant current aspect of the voltage divider be maintained.

In a similar manner, and through interconnecting terminals 30 and 31, connection is made to the tenths decade from the units decade. As before, the connection of the resistors, the relative resistance values of each, the arrangement for shorting, and so on are the same for the decades previously described. These resistors are given the subscript "s" to designate that they are a part of the *tenths* decade. They have absolute values $\frac{1}{10}$ that of the units decade.

In the tenths decade as shown, resistor 1_s is not shorted, while the others in the second group are shorted. This provides a voltage drop across 100 ohms, which is equivalent to 0.1 volt in the voltage divider of FIG. 2. In the tenths decade, resistors 2_s , 4_s , $2_s'$ are shorted by wipers 32, 33, 34, respectively, in order that the constant current aspect of the voltage divider be maintained.

Since the tenths decade is the last in this embodiment, a resistor $1_s''$ is connected between terminals 36, 37, which also connect to the beginning of the first and second groups of resistors; i.e., resistor 1_s and resistor $1_s''$. The value of resistor $1_s''$ in this embodiment is 100 ohms.

In FIG. 2 the feedback voltage E_o , that is, the adjustable voltage providing the desired output, appears between terminals 13 and 37. With the wipers in the positions shown in the figure the magnitude of this voltage is 47.1 volts. In order to preserve accuracy of the voltage divider function the circuit connected across terminals 13 and 37 should have a very high impedance, such as the input to a digital voltmeter, vacuum tube voltmeter, or the deflection plates of an oscilloscope. A specific ap-

plication for my device is the use with an analog voltage comparator for "go/no go" testing.

FIG. 3 shows the rotor contact side of the switch board or card, with the resistors for one decade, as in FIG. 1, indicated schematically and connected to the circuit wiring upon the board. Other circuit wiring is also required. This is normally positioned on the reverse side of the board. In FIG. 3 this other circuit wiring is shown dotted. Thus, the complete electrical circuit for a voltage divider decade is shown in one figure, with the significant contacts and circuit coating with the rotor wipers set forth according to the geometry of an actual embodiment. In this way all of the details of the invention is most easily comprehended.

15 The board 40 upon which etched or printed circuits may be formed is of usual material for this purpose, such as epoxy-filled fiberglass. While size is not definitive of invention herein, the board may be $3\frac{3}{8}$ " long by $1\frac{3}{4}$ " wide by $\frac{1}{16}$ " thick. Aperture 41 is provided as a bearing

20 for a short shaft attached to the rotor, which rotor carries the wiper contacts. Surrounding the aperture are five concentric tracks of stationary contacts. These are identified by designations T1 through T5. As will be noted more particularly in FIG. 4, the wipers are disposed at 25 differing radial distances, one to intercept the stationary contacts of one track. The several individual stationary contacts, such as 42, 43, 44, 45 in FIG. 3, are disposed to accomplish the shorting and unshorting routine set forth in the discussion of FIGS. 1 and 2.

30 Each small circle upon these contacts represents a connection hole from one side of the board to the other. Each hole either accommodates a soldered connection between printed circuit conductors on one side to the other, or, in the case of resistors required for the voltage dividing function, the soldered connection of the resistor pigtails to the conductors of the circuit board. Circle 46 is illustrative of the first use and circle 47 of the second use.

Several printed circuit conductors extend from the circumferential contacts to the resistors of the voltage divider. 40 For example, from the extended contact at track T1 conductor 48 connects to the left-hand side of resistor 2_t and continues onward, downward, and then to the right to form terminal 49. The several aligned terminals 50, 51, etc. are at an extending tab 52 of board 40 and are arranged to engage contacts in an elongated female socket, such as is known for making connections to external circuits in this technique. Similarly, from stationary switch contact 42 conductor 53 connects to the right-hand end of resistor 4.

50 It will be noted that the stationary contacts 42, 43, 44, 45, etc. have different sizes and shapes. This provides contact therewith by a given wiper for more than one switch position; which, in the case of the ten position switch illustrated, is 36° from one switch position to the next. Also, certain contacts extend to more than one track. As an example, the contact T4 is largely resident in track 4, but it also has a small upper extension to the right into the inner track 5.

60 The several resistors shown in FIG. 1; i.e., 1, 2, 4, 2', 1_t , 2_t , 4_t , 2_s , are also shown at the right side of card 40 in FIG. 3; with top and bottom connections on the card shown in full and dotted lines, respectively. Illustrative resistance values for these resistors have been given in 65 connection with FIG. 2. Resistor $1_s''$ is also shown.

The rotor, the wiper contacts and the thumbwheel are shown as a unit in FIG. 4. This assembly is shown to the same scale as employed for the board of FIG. 3. Shaft 60 fits into aperture 41 of board 40. This results 70 in the showing of FIG. 4 being inverted planarly. Thus, wipers 61, 62, 63, 64, 65, 66 bear upon tracks T1 through T5 upon the board.

It will be noted from FIG. 4 that the pairs of wipers 61, 62; 63, 64; and 65, 66 are spaced apart 120° circumferentially. Wipers 61 and 63 both bear upon outer track T1

of FIG. 3. The stationary contacts thereof, of which 42 and 44 are examples, are so formed that when wiper 61 is contacting a stationary contact wiper 63 is not so contacting, and vice versa. In this way a "hidden track" is provided, which results in five tracks functioning as six tracks. This reduces the diameter of my device and result in other understandable economies.

The wipers per se are formed of circular contact wire, such as the known Pchiney #7 material, and may be approximately $\frac{1}{64}$ inch in diameter by $\frac{3}{16}$ long. These wipers are spot-welded to beryllium copper or equivalent spring plates 67, 68 and 69 in pairs as shown. Each plate is provided with five fingers, as fingers 70 for plate 67. This allows a wiper to be attached to a finger to track upon any of the five tracks T1 through T5, as has been set forth. On plate 67 the fingers 70 corresponding to tracks 1 (outer) and 5 (inner) are provided with wipers 61 and 62. Since there is continuous metallic connection between these two wipers through plate 67, it is seen that contact between these wipers and stationary contacts of the tracks will result in a connection from one track to the other. When the fingers are to be used to support wipers the fingers are bent upward from the otherwise planar disposition of the plate, so that contact will be made only by bend near the free end of the wiper to the stationary contacts. The wipers are each given a slight bend at near the free end thereof so that the contact formed is suited for rotation of the rotor in either direction. This bend is indicated in FIG. 4 by shading upon each of the wipers.

On plate 68 the fingers 70 corresponding to tracks 1 and 2 are bent up and support wipers 63 and 64. On plate 69 the fingers 70 corresponding to tracks 3 and 4 are bent up and support wipers 65 and 66.

Each of the plates 67, 68 and 69 are fastened to an insulating rotor disk 71 by two eyelets 72. The rotor may be formed of a material such as epoxy-filled fiberglass. The rotor, in turn, is fastened in a thumbwheel housing 73 and correctly circumferentially positioned therein by intruding molded key 74. The thumbwheel has a plurality of projections 75, normally ten, and upon a flat surface adjacent to each projection there is engraved a numeral, the one adjacent to key 74 being the numeral "5." For a decade switch the numerals run from "0" through "9," counterclockwise in FIG. 4.

On the obverse side of the thumbwheel of FIG. 4 for a decade switch a ten hole and spring ridge circumferential detent may be positioned. This coacts with two plastic balls seated in depressions in a stationary switch housing that surrounds the thumbwheel. Since these elements are known and do not enter inventively into the structure being described they have not been illustrated. The thumbwheel may be molded of any suitable material, of which the phenolics are representative. Typically, the material used is colored black, or some other color for coding in the equipment in which the thumbwheels are used, with white or black filled numerals to indicate the position of the decimal thumbwheel.

While the use of printed circuits (and/or etched circuits) has been mentioned in the description of the preferred embodiment, it will be understood that hand-wired connections and inserted metallic stationary contacts may also be employed. The form and function of these alternate elements is essentially the same as those shown. Also, the use of known commercial resistors having pigtail conductors for connection at each end has been inferred in the description herein above. Alternately, the resistance required may be obtained by depositing metal films upon board 40 at appropriate places, as by vacuum deposition. For such an arrangement the configuration of the connecting conductors, such as 48 and 53, may be altered to give a longer path for a high resistance resistor and vice-versa.

In the multiple decades embodiment of FIG. 2, in which another decade is connected to the output of a given decade, the effective resistance of the following decade equals the resistance of the otherwise terminating resistor 1", thus such a resistor is not used. Note the absence thereof between terminals 22 and 23, and between terminals 30 and 31 in FIG. 2.

Still other modifications may be made in the characteristics of the circuit elements, details of circuit connections, and the arrangement size, proportions and shape of elements in the illustrative embodiment shown without departing from the scope of my invention.

Having thus fully described my invention and the manner in which it is to be practiced, I claim:

1. An adjustable voltage divider comprising
  - (a) a multiposition thumbwheel rotary switch having plural stationary contact tracks with each of said tracks having one rotary wiper and
  - (b) an additional track having plural stationary contacts, and two circumferentially spaced rotary wipers,
  - (c) a first group of series connected resistors which are connected to a first group of said stationary contacts, and
  - (d) a second group of series connected resistors which are connected to a second group of said stationary contacts and in series with said first group of resistors,
  - (e) means to rotate all of said rotary wipers in common,
  - (f) whereby, upon a resistor of said first group being shorted by a first wiper coactive with said first group of stationary contacts a resistor of said second group is unshorted by a second wiper at a different circumferential position than that of said first wiper, said second wiper coactive with said second group of stationary contacts, to alter an output voltage obtainable from said voltage divider by altering the resistance ratio between opposite ends of said first and second groups of series connected resistors.
2. The voltage divider of claim 1 in which
  - (a) an equivalent of a second said additional track is obtained by providing a spacing of approximately 120° between two circumferentially spaced rotary wipers, and
  - (b) providing stationary contacts on said additional track to contact only one of said two wipers at one given circumferential position, and only the other of said two wipers at another given circumferential position.
3. The voltage divider of claim 1 in which
  - (a) said one wiper for one said plural stationary track is disposed at a different position circumferentially than said one wiper for another one of said plural stationary tracks.
4. The voltage divider of claim 1 in which
  - (a) one of said one wipers is circumferentially disposed at the same position as one of said two circumferentially spaced rotary wipers, and
  - (b) two of said one wipers are located in common at another circumferential position.
5. The voltage divider of claim 4 in which
  - (a) each of said wipers that is circumferentially disposed at the same location as another wiper is electrically connected thereto.
6. The voltage divider of claim 1, which additionally includes,
  - (a) an insulating card, and
  - (b) said plural stationary contacts and electrical connections therefrom to said first and said second groups of resistors are affixed to said card.
7. The voltage divider of claim 1 in which
  - (a) the resistance of individual resistors in said first group of series connected resistors have the ratio one, two, four, two; and

(b) the resistance of individual resistors in said second group of series connected resistors have the ratio one, two, four, two and are connected in the same order to said second group of stationary contacts as are the said first group of said series connected resistors connected to said first group of stationary contacts.

8. The voltage divider of claim 1 in which

(a) an additional resistor is connected between one end of said first group of series connected resistors and the corresponding end of said second group of series connected resistors.

9. A multiple adjustable voltage divider according to claim 1 having

(a) a plurality of said thumbwheel switches,
 (b) means to connect all of said plurality of said first group of series connected resistors in series,
 (c) means to connect all of said plurality of said second group of series connected resistors in series, and
 (d) means to provide the adjustable voltage across all of said plurality of said second group of series connected resistors.

10

10. The multiple adjustable voltage divider of claim 9 in which

(a) the resistance of said first group of series connected resistors in one said plurality is a multiple of the resistance of said first group of series connected resistors in another of said plurality, and

(b) the resistance of said second group of series connected resistors in said one plurality is the same multiple of the resistance of said second group of series connected resistors in the same other of said plurality.
